Primary Examiner — Catherine A Tuttle(74) *Attorney, Agent, or Firm* — Stephen J. Weyer, Esq.;
James R. Hayne, Esq.; Stites & Harbison, PLLC(57) **CLAIM**

The ornamental design for a toy xylophone, as shown and described.

DESCRIPTION

FIG. 1 is a top, front and left side perspective view of the toy xylophone of our design.

FIG. 2 is a bottom, front and left side perspective view of the toy xylophone thereof.

FIG. 3 is a front elevation view thereof.

FIG. 4 is a rear elevation view thereof.

FIG. 5 is a left side view thereof.

FIG. 6 is a right side view thereof.

FIG. 7 is a top plan view thereof; and,

FIG. 8 is a bottom plan view thereof.

The dash-dash broken lines are included for the purpose of illustrating the portions of the toy xylophone that form no part of the claimed design.

1 Claim, 8 Drawing Sheets(56)
